MUSICAL INSTRUMENT

Santiago N. Montegrande, Delano, Calif.

Application November 4, 1938, Serial No. 233,877

2 Claims. (Cl. 84—296)

My invention relates to improvements in musical instruments and more particularly to stringed instruments of the class characterized as guitars and the like.

5 One of the principal objects of my invention is to provide a musical instrument wherein the head is so constructed and arranged to transmit the sound vibrations of the instrument from the strings thereof through a diaphragm to the air column, wherein they are amplified and qualified to produce an improved tone.

10 Another object of my invention is to provide an instrument of the above described character which is simple in construction, durable in use, 15 efficient in operation and economical in manufacture.

Other objects and advantages will be apparent from the following description, appended claims and annexed drawing.

20 Referring to the drawing wherein like reference characters designate like parts throughout the several views:

Figure 1 is a top plan view of my invention.

Figure 2 is a horizontal sectional view through 25 the head or body of the instrument illustrating a portion of the neck attached thereto.

Figure 3 is a detail sectional view taken on the line 3—3 of Figure 1.

Figure 4 is a detail perspective view of the 30 slider employed in the playing of the instrument.

Figure 5 is a detail perspective view of the pick.

In practicing my invention, I provide a musical 35 instrument 5 of a substantially guitar type equipped with a body 6 and which has detachably secured thereto a neck 7. The neck 7 is fashioned with the usual finger board 8 over which extend a pair of strings 9 the upper ends 40 of which are secured to adjustable pegs 10 mounted in the upper end of the neck in the usual manner. The lower ends of the strings line are secured to the upper wall 11 of the body 6 by means of a securing member 12 fastened 45 thereto as illustrated in Figures 1 and 3 of the drawing.

The upper wall 11 of the body 6 is fashioned with a circular opening 13 and subjacent said wall 11 and in registry with the opening 13 is a 50 hollow cylinder 14 secured to the bottom wall 15 of the body by means of screws 16. Interposed between the lower face of the wall 11 and the upper face of the cylinder 14 is a diaphragm 17, the latter being preferably constructed of relatively thin steel and which is secured between

said wall 11 and cylinder by means of screws 18. The diaphragm 17 is formed with a centrally disposed aperture 19 over which extends a bridge 20 secured to the upper face of the diaphragm 17 and said bridge supports the strings 9 in the usual manner. At one of the rear corners thereof, the body is offset laterally to provide an extended section 21, the upper end of which is apertured and fashioned with an outwardly flared circumferentially extending flange 22. The side wall of the body adjacent the section 21 is fashioned with a partition 23 which extends from said side wall to the lower side of the cylinder 14 and forms a substantially spiral passage between an elongated opening 24 formed in the cylinder and the section 21 as clearly illustrated in Figure 2 of the drawing.

In use, when the instrument is played, the diaphragm 17 is vibrated against the air column within the cylinder 14 and the tones are emitted 20 through the aperture 24 into the spiral passage 25 where they are amplified and pass outwardly through the flange 22. A slider 26 is employed for engagement with the strings 9 and a pick 27 is utilized for picking the strings in the manner 25 of a Hawaiian guitar.

The lower end of the neck 7 is fashioned with a dovetail 28 over which is secured a wear plate 29 and said dovetail plate is detachably secured within a dovetail socket member 29' secured to 30 the upper side wall of the body 6 as illustrated in Figures 2 and 3 of the drawing. A screw 30 secures the lower end of the member 29' to the lower end of the plate whereby to maintain the neck connected to the body. Removal of the 35 screw 30 permits the neck to be detached from the body whereby the instrument may be conveniently packed.

I claim:

1. In an instrument of the class described, a 40 hollow body formed with a laterally and outwardly disposed section and provided with side, lower and upper walls, said upper wall fashioned with a pair of spaced openings with one of the latter disposed substantially centrally of the 45 body and the other substantially centrally with respect to said section, a hollow cylinder formed with a sound emitting slot in one side thereof and disposed within said body, said cylinder fixed to said upper and lower walls and arranged axially and concentrically with respect to said first defined opening, a diaphragm secured between said upper wall and said cylinder and extending across said first defined opening, and a partition 50 fixed to said upper and lower walls and extend- 55

ing between said side wall and said cylinder adjacent said slot and said section and defining a substantially cochleous passage extending from said slot to within said section whereby sound emitted through said slot is amplified through said last defined opening.

2. The structure of claim 1 as set forth and defined therein including, a string supporting bridge member secured to said diaphragm for imparting vibration to the latter upon playing of strings carried on said bridge.

SANTIAGO N. MONTEGRANDE.
